UNITED STATES PATENT OFFICE.

EDSON R. REAMER, OF AMSTERDAM, NEW YORK.

THILL-IRON.

SPECIFICATION forming part of Letters Patent No. 626,564, dated June 6, 1899.

Application filed April 18, 1899. Serial No. 713,474. (No model.)

To all whom it may concern:

Be it known that I, EDSON R. REAMER, of Amsterdam, in the county of Montgomery, State of New York, have invented certain new and useful Improvements in Thill-Irons, of which the following is a complete specification, reference being had to the accompanying drawings.

The object of my invention is to produce an improvement in thill-irons by which the wooden shafts or thills are united to the cross-bar and hinged to the axle, respectively, whereby the irons may be originally fitted or subsequently repaired with facility and despatch without heating after they are once made.

According to the methods in ordinary use, a wagon-maker, especially in repairing a broken thill-iron, must weld the broken parts together and fit the iron to the wood after the welding process. In order to do this, it becomes necessary to apply the heated iron repeatedly against the wood or in close proximity thereto in order to adjust the proportions and cause the holes in the refashioned iron to register with the holes in the shafts. The application of the hot iron to the wood destroys any finish that the wood may possess and makes it necessary after a repair job to refinish the shaft. By my invention it is proposed to secure as perfect and rigid a fit between the several parts of the thill-iron as it would be possible to secure by welding the parts together, but through the employment of members which may be assembled, disassembled, and reassembled or in the use of which a new part may be substituted for an old as often as occasion may require without the employment of heat or without the necessity of any refitting of the parts except such as may be performed upon the cold metal by the use of ordinary tools.

In the accompanying drawings, Figure I is a perspective view of portions of one thill and cross-bar, showing my thill-irons attached on the under side after the usual manner. Fig. II is a longitudinal vertical section of the thill shown in Fig. I, the line of juncture of the cross-bar with the thill being indicated by dotted lines in the drawings. Fig. III is a perspective view of my thill-irons detached

from the shaft, but assembled as in use thereon.

Referring to the figures on the drawings, 1 indicates, by way of example of any ordinary or suitable thill, an ordinary wooden shaft, to which is secured, as by the usual tongue 2, (illustrated in Fig. II,) the cross-bar 3, that unites a pair of shafts and carries the singtonetree.

4 indicates the rear portion of the iron strap that is affixed to the part of the shaft 1 that is usually curved and which terminates in a coupling-eye 5. 6 indicates the forward terminal portion of the strap. In the ordinary thill-iron the straps 4 and 6 are continuous, and from them proceed the cross-bar 3. This tongue in devices heretofore used is either made integral with the strap or overlaps and is secured to the continuous strap.

By my invention the strap 4 and its forward portion 6 are, as described and illustrated, two separate pieces, whose opposing ends 7 and 8, respectively, are fitted snugly within terminal sockets in the cross-head 9 of a T-iron, whose tongue 10 extends underneath the cross-bar 3. The inner faces of the straps 4 and 6 are flush with the surfaces of the T-iron, composed of the cross-head 9 and tongue 10, and the respective surfaces of the straps and T-iron lie flat and smooth against the faces of the thill and cross-bar, to which they are respectively secured, as by any required number of bolts 11.

In practice the straps 4 and 6 are fitted to the T-iron and then to the thill and cross-bar, which are bored to receive the bolts 11, by which the several parts are united, as described and illustrated.

It is important in practice that the several parts of the thill-irons should be immovably united one to the other in order that each part may afford a firm union with the thill and cross-bar and that each part may afford a secure anchorage against the movement of any other part. It is for that reason that a firm union of the T-iron with the straps is provided and that a sufficient number of bolts is employed to secure the requisite stability of the several parts.

The T-iron may be made of any suitable material, preferably of malleable iron, that

- may be struck by a die or otherwise formed into required shape. Consequently, being made to a standard size, one may be substituted for another in repair jobs by merely 5 loosening the nuts 12 of certain of the bolts 11, applying the new piece, and bolting it in place. It is not even necessary to remove all of the nuts 12, but only so many as will permit the removal of the part to be renewed.
- 10 The new part may be secured without disturbing the position of the bolts, and all may be effected without the application of heat, as was suggested in the general statement of invention.
- 15 What I claim is—
1. The combination with a thill and cross-bar, of thill-irons consisting of a pair of straps secured to the thill and separated from each other, an intermediate T-iron whose cross-
  - 20 head is provided with terminal sockets fitting the ends of said straps, and a tongue project-

ing from the cross-head along the cross-bar, substantially as set forth.

2. An improvement in thill-irons, consisting of the combination with a T-iron whose 25 cross-head is provided with terminal sockets, of a pair of thill-straps whose opposing ends fit within the sockets, substantially as set forth.

3. A thill-iron consisting of a T-iron comprising a cross-head having terminal sockets, and a tongue projecting therefrom, the sockets being terminally defined and separated by the metal of the cross-head, whose surface is in the same plane with the tongue. 30

In testimony of all which I have hereunto subscribed my name.

EDSON R. REAMER.
